UNITED STATES PATENT OFFICE.

VICTOR E. BLACKBURN, OF BELLVIEW, NEW MEXICO.

RADIATOR PROTECTOR.

Application filed April 18, 1925. Serial No. 24,227.

To all whom it may concern:

Be it known that I, VICTOR E. BLACKBURN, a citizen of the United States, residing at Bellview, in the county of Curry and State of New Mexico have invented new and useful Improvements in Radiator Protectors, of which the following is a specification.

This invention relates to an attachment for an internal combustion motor, the general object of the invention being to provide means for preventing the radiator in the motor from freezing in cold weather.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawing wherein like characters denote like or corresponding parts throughout the several views, and in which:

Figure 1 is a view showing the invention applied to a motor vehicle.

Figure 2 is a plan view of Figure 1.

Figure 3 is a front view of the device with the front part thereof swung downwardly.

Figure 4 is a transverse sectional view of the device showing the same on a radiator.

Figure 5 is a section on line 5—5 of Figure 4.

Figure 6 is a section on line 6—6 of Figure 4.

Figure 7 is a sectional view of one of the nozzles.

In these views, 1 indicates a casing which is adapted to be placed against the front part of the radiator of a motor vehicle with an internal combustion engine. This casing is held in place by means of a bracket 2 which is fastened to the upper end of the casing and which has a hole therein to fit over the radiator filling spout. Brackets 3 are secured to the bottom of the casing and are fastened to the bottom of the radiator by the turn buttons 4 which engage slots 5 in the brackets. Thus the device is detachably held at the front of the radiator. The casing is provided with a front cover part 6 which is hinged to the casing at its lower end as shown at 7 and which is held in closed

position by the pins 8 which pass through tubular projections 9 on the cover part and on the casing. The casing is provided with an opening 10 in its lower end for the admission of air. A plurality of straps 11 are secured in spaced relation to the inner wall of the casing and these straps support strips 12 of asbestos or the like, the strips being of gradually increasing width as shown in Figure 4. A plate 13 is fastened to the lower end of the cover part 6 above the opening and has its ends curved and this plate is covered with a sheet 14 of asbestos or the like which acts to catch fuel falling from the strips 12 and to prevent this fuel from dropping through the opening 10. The air is caused to circulate through the casing by this plate which acts as a baffle plate. A pipe 15 extends into the casing through the top thereof and this pipe is provided with a transverse part 15' which has its ends bent downwardly and attached to nozzles 16 which are so arranged as to spray fuel upon the strips 12. The pipe 15 is connected to a supply tank 17 which may be held in the cowl of the vehicle by the cables 19 which have their ends connected to the eye bolts 20 on the running board of the vehicle. The flow of oil through the pipe is controlled by a valve 21.

From the foregoing it is seen that when the device is in operation the oil or gasoline will flow to the nozzle from the tank 17 through the pipes 15 and 15' and thus be sprayed upon the asbestos strips 12. The strips are lighted by opening the cover and then the cover is closed so that the heat produced by the burning fuel will heat the casing and thus prevent freezing of the water in the radiator. The entire device is provided with a lining 22 of asbestos or the like and a sheet 23 of the same material is placed around the nozzles.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A radiator heater comprising a casing having a hinged front part, means for fastening the casing to a radiator, wicks of

asbestos supported by the casing, nozzles in the casing above the wicks, a fuel supply connected with the nozzles and means for preventing the fuel dropping from the wicks
5 from passing from the casing.

2. A heater for radiator comprising a casing, means for detachably connecting the same to a radiator, a hinged front part for the casing, wicks of gradually increasing
10 width supported on the inner wall of the

casing, nozzles in the casing above the wicks for spraying the same with the fuel, a fuel supply connected with the nozzles, the bottom of the casing having an opening therein, a plate having curved ends 15 covering the opening and spaced above the same so that the air can enter the casing through said opening and a lining of asbestos for the casing and for the pipe.

VICTOR E. BLACKBURN.
